Arthur E. Paige,
Attorney.

UNITED STATES PATENT OFFICE

CHARLES H. DAVIES, OF PHILADELPHIA, PENNSYLVANIA

METHOD OF MAKING ARTIFICIAL LIMBS

Application filed August 15, 1931. Serial No. 557,274.

It is the object and effect of my invention to form an artificial limb of which the principal element is a tube of thin metal, preferably aluminum, which is so worked during the process of forming the limb as to impart to the metal the desired degree of rigidity necessary for resistance thereof to the stresses to which it will be subjected in actual use and which, otherwise, would have the effect of denting and otherwise distorting it.

As hereinafter described, such working includes first compressing a primarily cylindrical tube to form a tubular spindle with coaxial zones of different diameters at different regions of its length, in relative proportion to the diameters of the limb desired; then bending said spindle, transversely to its axis, to render said zones relatively eccentric, according to the shape of the limb desired. It may be bowed outwardly or inwardly, or forwardly or rearwardly, with respect to the medial line of the body of the wearer to match the oppositely counterpart natural limb of the wearer. Said eccentrically bent spindle is thereafter expanded to the eccentric shape of the limb desired, while defining that shape by a mold surrounding said spindle; such expansion being conveniently effected by subjecting the bent spindle to internal fluid pressure sufficient to distort it into the irregular curvatures of the mold. I have found a pressure of two thousand pounds per square inch satisfactory for that purpose.

Such a sheet metal limb is naturally resonant and use thereof is accompanied by a metallic sound caused by the vibration of the metal wall of the limb, unless means are provided to prevent the emission of sound vibrations from said wall. Therefore, a further object and effect of my invention is to provide such a tubular metal limb with an artificial skin of material which is not only incapable of transmitting any sound vibrations from the metal shell of the limb, but so constricts the latter as to suppress vibrations of the metal and render them inaudible. Such a skin is preferably formed of artificial cellulosic material expanded over and shrunk upon the metal of the limb so as to continu-

ally constrict said metal shell. Such an artificial skin is preferably formed of material which is inherently colored to resemble natural skin.

In the form of my invention hereinafter described, both the metal shell and the skin thereon are formed of seamless tubes in coherent relation.

My invention includes the various novel features of construction and arrangement and method of procedure hereinafter more definitely specified; the mold which defines the shape of the limb to which the metal tube is expanded is claimed in my copending application (215-31) Serial No. 555,275 filed August 15, 1931, for Letters Patent of the United States.

In said drawing: Fig. I is a side elevation of a cylindrical tube from which the artificial limb is to be formed.

Fig. II is a side elevation of a tubular spindle including coaxial zones of different diameters at different regions of its length, conveniently formed from the primarily cylindrical tube of Fig. I by comprising said tube while spinning it.

Fig. III is a front elevation of said spindle after it has been bent transversely to its axis to render said zones relatively eccentric, according to the shape of the limb desired.

Fig. IV is a front elevation of the bent tube shown in Fig. III after it has been expanded to the shape of the limb desired.

Fig. V is a side elevation of said tube shown in Fig. IV.

Fig. VI is a cross sectional view of said shell shown in Figs. IV and V, taken on the lines VI in those figures, showing a mold which surrounds said tubular shell while it is being expanded by internal fluid pressure.

Fig. VII is a sectional view of said shell similar to Fig. VI but showing it provided with a seamless artificial skin.

In said figures; the metal tube 1 shown in Fig. I, is primarily cylindrical and, preferably, of the largest diameter desired for the spindle 2, shown in Fig. II. Said spindle 2 is conveniently formed from said primarily cylindrical tube 1 by fitting within the latter a mandrel 3 which is of the shape desired for

the spindle 2 and then compressing said tube 1 upon said mandrel 3 while spinning said tube and mandrel and with the effect of making said spindle 2 of different diameters throughout its length in relative proportion to the different diameters of the artificial limb shell which it is desired to form therefrom.

As indicated in Fig. II, said spindle 2 is symmetrical with respect to its axis 5, but there is no natural limb which is thus symmetrical, but every natural limb includes zones of different diameters throughout its length which are in eccentric relation to each other. Therefore, I bend the spindle shell 2 in accordance with the eccentric shape desired for the artificial limb which is to be made therefrom. Such bending may be readily effected without kinking the metal, while said shell is packed with sand. Although Fig. III shows said spindle 2 distorted from its primarily coaxial form shown in Fig. II, by bending it in but one direction; it is to be understood that it may be bent transversely to its axis in several directions, for instance, it may be bent laterally if the limb to be formed therefrom is to be bowed or knock-kneed, and may be bent either forwardly or rearwardly or spirally, in accordance with the oppositely counterpart natural limb which it is to match.

For instance, said bent tubular spindle 2 shown in Fig. III may thereafter be expended to the eccentric configuration of the artificial limb shell 7 shown in Figs. IV and V by stretching the metal of its wall outwardly throughout its length. Such expansion is conveniently effected by subjecting said spindle 2 to internal fluid pressure, preferably of water, and two thousand pounds per square inch, while defining the shape of said shell 7 by a mold surrounding said spindle. As indicated in Fig. VI, such a mold may be of split tubular form comprising oppositely counterpart sections 9 and 10 respectively mounted in the mold frame members 11 and 12 and having an internal configuration corresponding with that of the metal shell 7, shown in Figs. IV and V. To effect such expansion, the opposite ends of said spindle 2 are respectively connected in fluid tight relation with conduits 14 at the opposite ends of the mold and through which the fluid under pressure is introduced to the interior of the spindle 2 with the effect of stretching and expanding the latter until it conforms to the irregular eccentric configuration of the interior of the mold which, as above indicated, corresponds with that of the metal shell 7, shown in Figs. IV and V, and which is known to the trade as a "shin".

However, it is understood that the process above described may be employed in the formation of an artificial thigh or forearm or upper arm.

In any case; I prefer to provide the metallic

artificial limb member thus formed, and which is a seamless tube, with an artificial skin 15 which, as indicated in Fig. VII, is also a seamless tube and preferably formed by taking a primarily cylindrical tube of skin colored artificial cellulosic material, for instance pyroxylin, and which is naturally hard, and softening it either by heating it in water or by application of a solvent such as an aqueous solution of cellulose acetate or an aqueous solution containing equal parts of acetone and ethyl alcohol. Then stretching it over the metallic limb shell, for instance the shell 7, and permitting said skin 15 to contract and set to hardened condition, thus constricting the metallic tube of the artificial limb and suppressing the natural tendency thereof to vibrate and emit sound vibrations.

Therefore, I do not desire to limit myself to the precise details of construction and arrangement and method of procedure herein set forth, as it is obvious that various modifications may be made therein without departing from the essential features of my invention, as defined in the appended claims.

I claim:

1. The method of forming an artificial limb, which includes forming a tubular metal spindle, open at each end, with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the shape of the limb desired.

2. The method of forming an artificial limb, which includes forming a tubular metal spindle, open at each end, with coaxial zones of different diameters at different regions of its length, in relative proportion to the diameters of the limb desired; then bending said spindle, transversely to its axis, to render said zones relatively eccentric, according to the shape of the limb desired, and thereafter expanding said bent spindle to the shape of the limb desired, while defining that shape by a mold surrounding said spindle.

3. The method of forming an artificial limb, which includes spinning a seamless metal tube to form a spindle, open at each end, with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the shape of the limb desired.

4. The method of forming an artificial limb, which includes spinning a seamless metal tube to form a spindle, open at each end, with coaxial zones of different diameters at different regions of its length, in relative pro-

portion to the diameters of the limb desired; then bending said spindle, transversely to its axis, to render said zones relatively eccentric, according to the shape of the limb desired; and thereafter expanding said bent spindle to the shape of the limb desired, while defining that shape by a mold surrounding said spindle.

to contract to solid form upon, and constrict, said metal tube.

In testimony whereof, I have hereunto signed my name at Philadelphia, Pennsylvania, this fifth day of August, 1931.

CHARLES H. DAVIES.

70

5. The method of forming an artificial limb, which includes compressing a seamless cylindrical metal tube to form a spindle, open at each end, with coaxial zones of different diameters at different regions of its length, in relative proportion to the diameters of the limb desired; and thereafter expanding said spindle to the eccentric shape of the limb desired, while defining that shape by a mold surrounding said spindle.

75

20. The method of forming an artificial limb, which includes compressing and spinning a primarily cylindrical metal tube to form a spindle, open at each end, with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

80

25. The method of forming an artificial limb, which includes compressing and spinning a primarily cylindrical metal tube to form a spindle, open at each end, with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

90

30. The method of forming an artificial limb, which includes forming a tubular metal spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

95

35. The method of forming an artificial limb, which includes forming a tubular metal spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

100

40. The method of forming an artificial limb, which includes forming a tubular metal spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

105

45. The method of forming an artificial limb, which includes forming a tubular metal spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

110

50. The method of forming an artificial limb, which includes spinning a primarily cylindrical metal tube to form a spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

115

55. The method of forming an artificial limb, which includes spinning a primarily cylindrical metal tube to form a spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

120

60. The method of forming an artificial limb, which includes spinning a primarily cylindrical metal tube to form a spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

125

65. The method of forming an artificial limb, which includes spinning a primarily cylindrical metal tube to form a spindle with coaxial zones of different diameters at different regions of its length, in relative proportion to the diameters of the limb desired; then bending said spindle, transversely to its axis, to render said zones relatively eccentric, according to the shape of the limb desired; and thereafter expanding said bent spindle to the eccentric shape of the limb desired, while defining that shape by a mold surrounding said spindle.

CERTIFICATE OF CORRECTION.

Patent No. 1,884,589.

October 25, 1932.

CHARLES H. DAVIES.

It is hereby certified that error appears in the printed specification of the above numbered patent requiring correction as follows: Page 1, line 65, for serial number "555,275" read "557,275"; and line 75, for "comprising" read "compressing"; and that the said Letters Patent should be read with these corrections therein that the same may conform to the record of the case in the Patent Office.

Signed and sealed this 6th day of December, A. D. 1932.

(Seal)

M. J. Moore,
Acting Commissioner of Patents.
